NOZZLE

Filed May 16, 1927

UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

NOZZLE

Application filed May 16, 1927. Serial No. 191,704.

This invention relates in general to a novel and improved nozzle, and the method of making it.

An important object of the invention is the provision of a nozzle which is made up of different sheet metal parts, one of which is of relatively soft or light weight metal adapted to be ruptured or severed for dispensing purposes.

10 Another important object of the invention is the provision of a strong and durable pouring or dispensing nozzle, which is easily severable or tearable along a directed line of severance.

15 Another important object of the invention comprises the provision of a nozzle of two different sheet metal parts pressed tightly into liquid-tight sealing engagement, one within a recess of the other to provide a non-projecting, smooth, outer nozzle surface.

20 Another important object of the invention comprises the provision of a nozzle made up of sheet metal parts of different strengths pressed together in liquid-tight metal-to-metal sealing contact to eliminate an additional sealing or binding medium, such as solder between the parts.

25 Still another important object of the invention is in the method of producing the nozzle in an efficient, simple, and economical manner.

30 Numerous other objects and advantages of the invention will be apparent as it is better understood from the following description, which, taken in connection with the accompanying drawing, discloses a preferred embodiment thereof.

In the drawing:

35 Fig. 1 is a perspective of a well-known type of container embodying the improved nozzle of the present invention;

40 Fig. 2 is a sectional perspective of two different sheet metal blank parts constituting the nozzle;

45 Fig. 3 is a fragmentary vertical cross-section of upper and lower die members with blanks as shown in Fig. 2 in position to be operated upon;

50 Fig. 4 is a view similar to Fig. 3, showing

the die parts brought together with the nozzle parts therebetween; and

Fig. 5 is a vertical section through a completed nozzle, also showing an auxiliary screw cap applied thereto.

In the present invention, the nozzle comprises a neck part with an inwardly extending flange at the top to form a pouring opening which is sealed with a cap made of relatively soft metal, such as taggers' tin, which is easily ruptured or severed but is pressed in liquid-tight sealing engagement with the neck piece to form a permanent closure and may be indented or scored to form a definite line of severance for the removal of the contents of the receptacle by a customer.

55 Referring more particularly to the drawing, a sheet metal container 11 has a bottom 12 and a top 13 seamed or secured thereto. A nozzle 14 is soldered or secured to an upstanding flange 15 of the top 13.

60 The nozzle is produced from a neck part 16 of sheet metal of ordinary strength and a cap part 17 of relatively soft metal, such as taggers' tin which is easily ruptured or severed. The neck part is formed with an inwardly extending flange 18, and in order to complete the nozzle the cap part 17 is pressed into a liquid-tight metal-to-metal sealing engagement with the neck piece, as shown in 65 completed form in Fig. 5.

65 In order to form a sealing engagement between the neck and cap pieces 16 and 17, a pair of upper and lower die members 19 and 20 are provided, the upper member being slid- 70 able in an annular die member 21 and having at its lower face an annular marking ridge or bead 22. These die members 19 and 21 are held in yielding engagement with respect to each other by means of a spring 23 surrounding a stem 24 of the die member 19, which permits the latter to be moved within the recess of the outer die member 21.

75 The lower die core member 20 has a movable auxiliary outer die ring member 25 annularly spaced from the core 20 a distance equal to the thickness of the sheet metal of the neck piece 16, so that a blank neck piece may be inverted over the core 20 and placed between it and the outer die ring 25.

The die ring 25 is provided with recesses 26 in its lower edge, to receive the upper ends 5 of pins 27 having stop heads 28, and the shanks of the pins have a slideable engagement in holes 29 in a flange or extension 30 at the lower end of the die member 20. Springs 31 surround the pins 27 between the upper face 10 of the flange 30 and the lower end of the die member 25 and hold the latter in an upwardly extending position, as shown in Fig. 3, but permit this die member 25 to be yieldingly compressed downwardly when the upper die member descends and operates upon the blanks, as shown in Fig. 4.

15 In order to properly seat the neck member 16 upon the upper end of the core die member 20, the top edge of the die member is formed with an annular recess 32 to seat the flange 18 and to form a space for receiving an inwardly pressed ridge or bead 33 on the under side of the blank 17 (Fig. 5) formed by the marking bead 22 of the upper die member 19. Also around the upper edge of the die member 20 is a recess 34 to permit the side wall of 25 the neck member 16 to be struck inwardly and laterally recessed a distance equal to the thickness of the downwardly turned edge 35 of the cap member 17, this downwardly turned flange being of a height corresponding 30 to the height of the recess 34 and presenting a smooth outer surface level with the outer surface of the neck body wall when the die forming operation is completed, as shown in Fig. 4.

35 The ring die member 25 is also preferably formed with an inner annular recess 36 for seating a cap blank 17 therein, as shown in Fig. 3, flush with the top of the die member 20 and resting upon the upper edge of the flange 18 of the neck member 16 before the die forming operation, as shown more clearly in Fig. 3. The die member 21 is formed at its lower edge with an annular shoulder 37 corresponding to the recess 36 so that it becomes seated therein as shown in Fig. 4, and the inner edge 38 of the shouldered portion is rounded away so that in the operation of the die members the depending flange 35 of the cap member 17 is formed downwardly over 50 the neck member 16 by the engagement of this rounded edge 38 therewith.

With this construction it will be seen that when the upper and lower dies are brought together, as shown in Fig. 4, the flange of the 55 soft metal cap member 17 is wiped over the upper edge of the nozzle neck member 16 by the co-operating action of the die members 21 and 25, thereby slightly necking-in the top part of the neck, and is further pressed 60 tightly against the top by the beading ridge 22, thereby indenting this portion of the cap member 17 and forming a definite line of severance so that a cutting tool may be directed along this line to facilitate the cutting 65 out of the central part of the soft metal cap

for the removal of the contents of the receptacle by the consumer. The cap member 17 is struck into the recess formed at the top of the neck member 16, so that a liquid-tight metal-to-metal contact is thus produced between the rigid metal of the neck piece and the softer metal of the cap piece, and a flush or smooth outer surface is formed between them.

If desired, the under and inner side of the soft metal cap 17 may be coated with any suitable lining material, or only that area of the soft metal cap which comes in contact with the rigid metal of the neck part may be so coated.

In order to protect the soft metal cap during transportation and until the contents of the can is to be used, an auxiliary screw cap 39 is applied to the nozzle, the neck portion of the nozzle being correspondingly screw-threaded for this purpose in a well-known manner.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

1. A nozzle comprising two sheet metal parts, one of relatively softer and more easily tearable material than the other, the softer material being pressed tightly over the other material to make a liquid-tight metal-to-metal joint with a smooth and flush outer surface, and marked to indicate a preferred line of severance for forming a pouring opening.

2. A nozzle comprising a sheet metal neck piece with an outer flanged opening, and a cap of soft, easily severable metal applied over the opening and fitting tightly in a recess at the outer end of the neck piece so that the surface joint between the two pieces is flush and smooth and the cap piece being formed with a definite marking inside of the flange of the neck piece to indicate a preferred line of severance thereof.

3. In a sheet metal nozzle, a neck piece of relatively strong and rigid material, and a cover fitting over the end of the neck piece of relatively soft, easily tearable sheet metal, the cap being pressed over the end of the neck piece to make a liquid-tight engagement therewith, and the neck piece being annularly recessed and necked-in to receive the edge of the cap member applied thereto and forming a smooth flush outer surface therewith.

4. A nozzle for cans, having a top provided with a dispensing aperture, and a separate seal of soft metal covering said top and aperture and extending down on the side of the

nozzle, the lower edge of said seal and a corresponding part of the nozzle being indented inward in liquid-tight contact with each other.

5. An article of manufacture consisting of a cylindrical sheet metal nozzle having a soft metal cover formed with a depending marginal part, the nozzle having a lateral recess and an inturned flange at its upper end, the 10 depending marginal part of the cover fitting in said recess substantially flush with the lower part of the nozzle.
